UNITED STATES PATENT OFFICE.

FRANCIS W. BRADY, OF ENGLEWOOD, NEW JERSEY.

STARTING DEVICE FOR INTERNAL-COMBUSTION ENGINES.

No. 849,324.

Specification of Letters Patent.

Patented April 2, 1907.

Application filed August 11, 1904. Serial No. 220,381.

To all whom it may concern:

Be it known that I, FRANCIS W. BRADY, of Englewood, in the county of Bergen and State of New Jersey, a citizen of the United States, have invented certain new and useful Improvements in Starting Devices for Internal-Combustion Engines, of which the following is a specification.

This invention relates to an internal-combustion engine wherein a heated vaporizer for a liquid hydrocarbon is employed and wherein means are required for starting the engine in order to generate the heat necessary to get the vaporizer into efficient operation.

The object of the invention is to provide the engine with a simple and efficient starting device or means wherein alcohol or some similar very volatile and combustible liquid is used in the starting device to produce the explosive charge.

In the accompanying drawings, which illustrate an embodiment of the invention and its application to an engine, Figure 1 is a side elevation of an internal-combustion engine provided with the present invention. This is a general view on a small scale. Fig. 2 is a vertical section of the engine on the same scale as Fig. 1, but in a plane coincident with the axis of the engine-shaft. Fig. 3 is a sectional detail view of the device on a much larger scale than the principal views. Fig. 4 is a horizontal section at the line x^4 in Fig. 3. Fig. 5 illustrates a slightly-modified form of device controlling the admission of the alcohol or other volatile liquid.

Referring, primarily, to Figs. 1 and 2, 1 is the bed-plate of the engine; 2, the main shaft; 3, the cam-shaft; 4, the cylinder; 5, the crank; 6, the piston; 7, the piston-rod; 8, the combustion-chamber; 9, the vaporizer, which communicates with the combustion-chamber through the pipe 26 and the main vapor-inlet valve 27; 10, the pump for pumping the liquid hydrocarbon to the vaporizer; 11, the inlet for air to form part of the explosive charge, and 12 the means for operating the igniter. These features only relate to the present invention incidentally. In Fig. 1, 13 is a holder for alcohol, and 14 is a pipe to supply the alcohol to the engine, as will be hereinafter explained.

Referring now to the detail views, Figs. 3 and 4, 15 is an L-shaped conduit connected with the air-inlet 11 and at the other end opening into the combustion-chamber 8.

The passage through the conduit is controlled by an air-inlet valve 16, provided with a stem 17. This stem passes out through the wall of the chamber 15 and through a long guide-bearing 18, and the valve 16 is held up to its seat by a spring 19. When the piston descends in the operation of the engine, the valve 16 is opened by pressure on the upper end of its stem, effected through the medium of a rocker 23, actuated by an eccentric 24 on the shaft 3 and a rod 25, as seen in Figs. 1 and 2. The upper end of the valve-stem 17 passes loosely through the end of the rocker-arm and is supported therein by the pin 29. When the valve 16 is opened, air enters the combustion-chamber from the air-inlet 11; and the vapor is fed through the opening of the vapor-valve at the proper time by the eccentric 28. This is the operation when the engine is running in the usual manner, the vaporizer being then efficient from the heat; but at starting the engine when the vaporizer is cold and inoperative the device now to be described is employed. The stem 17 of the valve where it plays in the long bearing 18 is reduced in diameter to a suitable extent, so as to form an annular chamber 20 about the stem, and the pipe 14 from the holder 13 opens into this chamber, so as to supply alcohol thereto when the cock 21, controlling said pipe, is opened. In the stem 17 are grooves 22, one or more, as required, leading from the chamber 20 down along the stem far enough to open as ports 23 into the combustion-chamber, as seen in dotted lines in Fig. 3, when the stem is depressed to open the valve 16.

The operation is simple. When the engine shall have been at rest for a time and it is desired to start it, the cock 21 is opened and the fly-wheel of the engine rotated. The effect of this is to draw in air at the inlet 11, to press down and open the valve 16 to about the extent or position seen in dotted lines in Fig. 3, and to permit or cause the alcohol to flow through the grooved ports 22 and down the valve-stem, where it vaporizes and mixes with the inflowing air to form an explosive mixture, which is then exploded. This operation sets the engine in motion, and as soon as the vaporizer becomes efficient from the heat of the exhaust the cock 21 is closed, and thereafter the vapor is supplied through the main vapor-valve 27.

Fig. 5 shows a slightly-modified con-

struction of the device for controlling the admission of the alcohol. In this case the annular chamber 20 is formed in the bearing for the stem, and only the ports 22 are formed in the stem. The construction will be obvious from the drawing.

It will be noted in the construction herein shown the valve-stem does not act as a valve-plug to cut off a cross-passage, nor as a plunger to force out the liquid. The longitudinal movement of the stem opens channels formed by the flutes or grooves in the stem for the flow of the liquid along the stem into the air-passage.

Obviously this invention is not restricted to the use of alcohol as a highly-volatile liquid for starting the engine; but alcohol is preferred.

Having thus described my invention, I claim—

1. An internal-combustion engine having an air inlet and conduit, a valve controlling the admission of air to the engine through said conduit, a chamber about the valve-stem, an inlet to said chamber for supplying fluid hydrocarbon thereto, and a duct in the valve-stem to connect the fluid-chamber with the air-conduit when the valve is open.

2. An internal-combustion engine having an air inlet and conduit, a valve controlling the admission of air to the engine through said conduit, a stem on the valve, a bearing for said stem, a chamber between the stem and its bearing, an inlet to said chamber for supplying fluid hydrocarbon thereto, and ducts in the valve-stem to connect the fluid-chamber with the air-conduit when the valve is open.

3. An internal-combustion engine, having

an air inlet and conduit, a valve controlling the admission of air to the engine through said conduit, a stem on the valve, a duct in said stem, a bearing which embraces the valve-stem and closes the duct when the air-valve is closed, and means for supplying a fluid hydrocarbon to said duct.

4. An internal-combustion engine, having an inlet and conduit for air, a valve controlling said conduit, the longitudinally-grooved stem of said valve, and means for supplying a volatile liquid to the incoming air at starting to form an explosive charge, said means comprising a holder for the volatile liquid, a conduit leading therefrom to the valve-stem, a cock controlling said conduit and a bearing about said stem which cuts off the flow of liquid to the air-conduit when the air-valve is closed.

5. An internal-combustion engine, having an inlet and conduit for air to the engine, a valve controlling the influx of air, the stem of said valve having formed in it an annular chamber 20 within the bearing of the stem, and longitudinal grooves 22, forming ports, a holder 13 for a volatile liquid, a pipe 14 connecting said holder with the chamber 20, and a cock 21, in and controlling the flow through said pipe, said ports being so disposed that they are closed when the air-valve is closed and open when said valve is open.

In witness whereof I have hereunto signed my name, this 10th day of August, 1904, in the presence of two subscribing witnesses.

FRANCIS W. BRADY
